UNITED STATES PATENT OFFICE.

MICHAEL J. MCLOUD, OF NEW YORK, N. Y.

SIPHONIC FLUSHING APPARATUS.

1,349,683.

Specification of Letters Patent. Patented Aug. 17, 1920.

Application filed October 17, 1919. Serial No. 331,328.

To all whom it may concern:

Be it known that I, MICHAEL J. MCLOUD, a citizen of the United States, and a resident of the borough of Manhattan, city, county, 5 and State of New York, have invented certain new and useful Improvements in Siphonic Flushing Apparatus, of which the following is a specification.

My improvements relate to flushing apparatus of the siphon type used in connection with elevated tanks for effecting the temporary flooding and washing out of water closets etc.; and my object is to attain a simple, cheap, solderless structure of few 10 parts, of direct action, and affording the least possible resistance thereto, while easily capable of regulation and control, all as hereinafter fully set forth; the invention consisting in the specific construction, arrangement and combination of parts described and claimed, and distinctive features being the form of the goose neck, the construction of the starter piston and its valve flaps; and of the tube and sleeve for controlling and limiting siphonic action.

In the accompanying drawings,

Figure 1, is a vertical sectional elevation of a water tank equipped with my improved flushing apparatus;

Fig. 2, is a central vertical section of my siphonic flushing means, upon a larger scale than in Fig. 1, showing the starter piston raised, and the siphonic control tube lowered;

Fig. 3, is a perspective view of the starter piston and valves;

Fig. 4, is a central longitudinal section of one construction of my siphonic control sleeve and tube;

Fig. 5, is a central longitudinal section of another construction of my siphonic control sleeve and tube;

Fig. 6, is a cross section taken upon the plane of line 6—6, Fig. 5;

Fig. 7, is a view of the under side of the starter piston;

Fig. 8, is a section thereof taken upon the plane of line 8—8, Fig. 7;

Fig. 9, is a detail view of the starter piston flaps.

T, represents any kind of a flushing tank or reservoir of ordinary or desired construction, I, being the water inlet valve controlled by the float F, and rod f, in a manner well known in the art.

S, is my siphonic flushing device, considered as a whole. Its stationary parts consist essentially of the discharge tube d, the goose neck g, the starter cylinder c, and the siphon-break tube b. The discharge tube 60 d, constitutes the stand pipe on which the other parts are supported. It is formed with external screw threads d', d'', (Fig. 2) at base and top; the thread d', at the bottom screwing into the female threaded upper 65 end of the coupling pipe a, which latter extends through and projects beyond the floor t, of the tank T. The lower portion of the coupling a, is externally screw threaded for engagement with a lock nut n, and the female threaded upper end of the flushing pipe e, which latter extends to the water closet basin or other article to be flushed.

The lower end of the throat g', of the goose neck g, is female threaded for engagement with the male thread d'', on the upper end of the stand pipe d, and the lower portion of the inverted trumpet shaped mouth g'', of the goose neck g, is also female screw threaded for engagement with the external 80 screw thread c', upper end of the starter cylinder c. This inverted trumpet-shaped mouth g'', of the goose neck g, is a peculiar and novel feature of my construction and arrangement of parts, covering and including, 85 as it does, the whole area of the upper end of the starter cylinder c, and converging from thence gradually and uniformly into the cross area of the discharge passage g, g', d, so as to present lines of least resistance to 90 the outflow of water from the tank T, as hereinafter set forth.

In axial alinement with the center of the starter cylinder c, the trumpet shaped mouth portion g'', of the goose neck g, is formed 95 with the cylindrical bearing sleeve g'', for the lateral support and control of the piston rod p, of the starter piston P.

In a similar manner the inlet port g'', for the air break is positioned in the throat 100 g', in approximate axial alinement with the center of the discharge pipe d, said inlet port g'', being formed in a nipple cast integral with the goose neck g. The outer extension of this nipple is female threaded for the reception of the externally threaded upper end of the siphonic break tube b, which is pendent therefrom, extending downward parallel to the discharge pipe d, to the same 105 level as the open bottom of the starter cylinder 110.

der c , or approximately so,—*i. e.*, to a level slightly above the bottom or floor t , of the tank T .

The siphonic break pipe b , is provided for 5 the admission of air to the goose neck g , to terminate siphonic suction therein when the water level in the tank T , is lowered to a prescribed level by the discharge of water therefrom. If the break pipe b , were continuous without opening to tank except at 10 its lower extremity it is obvious that the latter would prescribe the low water level of the tank T ; but in order to afford means for regulating the height of this prescribed 15 level, I form said siphonic break pipe b , either with apertures b' , b^2 , b^3 , at different heights, or with one or more continuous longitudinal apertures b^x , (Figs. 5 and 6) as may be preferred; and also provide the 20 25 said break pipe b , with an adjustable regulator sleeve R , by means of which the level of air admission to the break pipe may be prescribed to meet the varying requirements and exigencies of use.

The regulator sleeve R , is a tube of 25 slightly greater main diameter than the siphonic break tube b , its upper extremity being contracted to form a close-fitting cylindrical bearing portion r , which contacts 30 with the exterior of the break tube snugly, and with sufficient frictional resistance to sustain the sleeve R , on the tube b . That is to say, the regulator sleeve R , is slideable on the air break tube b , but also sufficiently 35 adherent thereto to admit of its being positioned as desired along the length thereof.

Either end of the regulator sleeve R , may be used to prescribe the low water level in the tank T . Thus in Figs. 1 and 5, the lower 40 end thereof is shown as uncovering the lower apertures b' , in one case, and the lower end of the continuous longitudinal slot b^x , in the other; while in Fig. 2, the upper extremity of the regulator sleeve R , is withdrawn below the upper apertures b^3 , of the break tube b ;—the result being the same in either case in that the horizontal level at 45 which air shall be admitted to the break tube as the water recedes from the tank is prescribed by said regulator sleeve, which thus also, in other words, determines the low water level of the tank, and hence the 50 volume of water to be discharged therefrom by siphonic action through the flushing apparatus.

The advantage of the continuous longitudinal slot b^x , in the break tube b , shown in Fig. 5, is that it affords greater scope and delicacy of adjustment of low water level 55 as compared with the apertures b' , b^2 , b^3 , at different heights in said tube b . Otherwise the function of the regulator sleeve R , is essentially the same in either case.

The upper end of the piston rod p , is connected by a link l , with the usual actuating

lever L . The lower extremity of the piston rod p , is screw threaded and engages with the female threaded boss p' , in the center of the cross bar p^2 , of the annular rim p^3 ,—said rim p^3 , and cross bar p^2 , constituting 70 the piston base upon the upper side of which are mounted the two flap valves v , v . These flap valves are die made duplicates, only reversed in position as related to each other, as will be understood by reference to Fig. 9, 75 particularly,—the knuckles v' , v' , interlocking and being coupled together by pintles q , q , as shown in Figs. 7 and 8. That is to say, two pintles q , q , are used, positioned one on each side of the piston rod p , their 80 inner ends being screw threaded and bent over to pass through holes formed for the purpose in the cross bar p^2 , and the protuberant ends of the pintles being then secured by clench nuts q' , q' . 85

This construction of flap valve piston is simple, cheap, and effective, being well adapted to the requirements of continuous use in flushing apparatus of this character.

The operation of my improved flushing apparatus is substantially the same as of others of this class, the novelty in the present case consisting essentially in the specific structure. Thus, the lifting of the piston P , raises water into and beyond the goose neck g , thereby starting siphonic suction for the withdrawal of the flushing water through the discharge pipe d ,—the flap valves r , r , of course opening automatically for the purpose when the piston has reached the limit 100 of its up stroke, and remaining open during the descent of the piston to normal position, and as long as the siphonic flow of water is maintained through the starter cylinder c , goose neck g , and discharge pipe d . When 105 the water thus withdrawn from the tank lowers the water level therein to the height of air admission to the break tube b , prescribed by the regulator sleeve R , air ascends into the goose neck g , and siphonic action 110 terminates; and this is accomplished without gurgling or sucking noise because the air break inlet g' , injects the air into the throat g' , of the goose neck g , below the inner apex g^x , of the goose neck g , as shown 115 in Figs. 1 and 2,—this being an important and distinctive feature of my construction of apparatus, and one which renders it practically noiseless in operation in that the cause is eliminated by the introduction of 120 the siphonic air break directly into the downward flow of water below the turning point g^x , as above stated.

It is to be noted that the several parts of my apparatus are assembled and united by 125 screw threads entirely, obviating the use of solder, which is objectionable for obvious reasons; that the whole device is simple both in structure and operation; and that ample provision is made for economizing the use 130

of water and limiting the quantity flushed to the actual needs and requirements of work to be accomplished.

What I claim as my invention and desire to secure by Letters Patent is,

- 5 1. In siphonic flushing apparatus of the character designated, in combination with the starter cylinder and piston, discharge pipe, and siphonic air break tube and regulator sleeve, a goose neck interposed between the starter cylinder and the discharge pipe and formed with an inverted trumpet shaped mouth portion inclosing the upper end of the starter cylinder and depending air break inlet between such mouth and the siphonic air break tube, said trumpet shaped mouth portion being formed with a cylindrical bearing sleeve for the piston rod in axial alinement with the center of the starter cylinder, for the purpose described.
- 10 2. In siphonic flushing apparatus of the character designated, in combination with the starter cylinder and piston, discharge pipe, and siphonic air break tube and regulator sleeve, a goose neck interposed between the starter cylinder and the discharge pipe and formed with an inverted trumpet shaped mouth portion inclosing the upper end of the starter cylinder, and with a siphonic air break inlet port depending in alinement with the discharge tube intermediate the same and the goose-neck and opening into the discharge throat below the apex of the turn bend of the neck, for the purpose described.
- 15 3. In siphonic flushing apparatus of the character designated, in combination with the starter cylinder and piston, discharge pipe, and siphonic air break tube and regulator sleeve, a goose neck interposed between the starter cylinder and the discharge pipe and formed with an inverted trumpet

shaped mouth portion inclosing the upper end of the starter cylinder, said trumpet shaped mouth portion being formed with a 45 cylindrical bearing sleeve for the piston rod in axial alinement with the center of the starter cylinder, said goose neck being also formed with a siphonic air break inlet port depending in alinement with the discharge 50 tube intermediate the same and the goose-neck and opening into the discharge throat below the apex of the turn, for the purpose described.

4. In siphonic flushing apparatus of the character designated, in combination, a starter cylinder and piston, a discharge pipe, a goose neck interposed between the starter cylinder and the discharge pipe and formed with an inverted trumpet-shaped mouth portion inclosing the upper end of the starter cylinder, said trumpet shaped mouth portion being formed with a cylindrical bearing sleeve for the piston rod in axial alinement with the center of the starter cylinder, said 60 goose neck being also formed with a siphonic air break inlet port depending in alinement with the discharge tube intermediate the same and the goose-neck and opening into the discharge throat below the apex of the 70 turn bend of the goose neck, an air break inlet tube connected with said air inlet port in the goose neck and formed for the admission of air at different levels, and a regulator sleeve fitting over said air break inlet tube of larger mean diameter than the latter and formed with a contracted cylindrical bearing portion for slidable frictional contractual engagement with the said air inlet break tube, for the purpose described.
